UNITED STATES PATENT OFFICE.

ANTHONY GUSTIANA, OF SUDBURY, ONTARIO, CANADA.

LIFTING-JACK.

1,400,054.

Specification of Letters Patent. Patented Dec. 13, 1921.

Application filed April 18, 1921. Serial No. 462,124.

To all whom it may concern:

Be it known that I, ANTHONY GUSTIANA, of the town of Sudbury, in the Province of Ontario, Canada, have invented certain new and useful Improvements in Lifting-Jacks.

My invention relates to improvements in lifting jacks and the object of the invention is to devise a jack which will have a maximum length of lift and yet such as will be 10 compact to take up a minimum space when not in use and at the same time to devise means whereby the operation may be readily reversed without moving the hands from the operating lever and it consists essentially 15 of the arrangement and construction of parts as hereinafter more particularly explained.

Figure 1 is a sectional view through my jack.

Fig. 2 is a detail sectional view of the operating parts of my jack shown in the position they assume during the lowering operation and with the operating lever in the lowered position.

Fig. 3 is a similar view to Fig. 2 showing 25 the parts in the position they assume with the operating lever in the raised position.

Fig. 4 is a plan sectional detail on line 4-4 Fig. 3.

Fig. 5 is a sectional detail showing two 30 portions of my lifting column and a means for locking them together.

Fig. 6 is a sectional detail on line 6-6 Fig. 1.

Fig. 7 is a detail view of the operating 35 lever and handle.

In the drawing like characters of reference indicate corresponding parts in each figure.

1 indicates a casing the body of which is 40 circular and formed by two side walls 2 and 3 connected together by the wall 4. The bottom of the casing 1 is provided with an angular block portion 5 to provide a flat bottom for the casing when in the operative position on the ground. The casing 1 is provided with an opening 6 through which the lifting column is adapted to pass. 7 is a cross wall extending vertically from the inner side of the opening 6 to form a vertical 45 guide through which the lifting column is adapted to pass as will hereinafter be explained. Each wall 2 and 3 is provided with a groove 8 a portion of which is concentric to the center of the casing. The inner end 50 of the groove 8 terminates adjacent to the

vertical cross wall 7. The opposite end of the groove 8 extends vertically upward at the outside of the wall 7 and is provided intermediate of its length with an offset portion 9.

10 is a lifting column which is formed by a series of sections 11, 12, 13, 14, 15, 16, and 17 hingedly connected one with the other as will be clearly seen on referring to Fig. 5. In this figure it will be seen that each section is provided with an end recess 18 and the next adjacent section with a lug 19 extending into such recess and through which and the side walls of the recess 18 extends a hinged pin 20. Each section is 15 provided in one end with a cross slot 21 which is curved concentrically to the center of the hinged pin 20. It will be noted also that the outer wall of each slot 21 is cut shorter than the inner wall. Each next 20 adjacent section is provided with a correspondingly formed cross lug 22 which fits into the cross slot 21, the base of such lug being enlarged at 23 to fit the cut away portion of the wall of the slot 21. Each lug 25 22 is provided with a cross orifice 24. The wall of the recess 18 dividing such recess from the cross slot 21 is provided with an orifice 25. Each side wall of the recess 18 is provided with a slot 26. 27 is a locking 30 member extending between the side walls of the recess 18 and provided at its ends with pin projections 28 extending through the slots 26 into the grooves 8 formed in each side wall 2 and 3 of the casing 1. 29 35 is a locking pin extending from the locking member 27 and into the orifice 25. In its normal or unlocked position the locking pin 29 extends only partially through the dividing wall formed between the recess 18 40 and the cross slot 21. In order to hold the locking member definitely in place I have provided a spring finger 30 having recesses 31 and 32 spaced apart and adapted to receive the sharp projection 33 extending from the locking member 27. 31^x is a housing which is carried by the side walls of the casing 1 and by the block 5. 34 is a slot formed in the housing 31^x and through which the operating lever herein- 45 after described passes. 35 is the operating lever of my jack provided at its inner end with a forked end 36. The operating lever 35 is pivotally mounted between the side walls of the housing 31^x upon a pin 37. 38 50 55 60 65 70 75 80 85 90 95 100 105 110

is an operating pawl which is pivotally mounted upon a pin 39 between the arms of the jaw 36. The outer face of each section of the lifting column 10 is provided 5 with a ratchet rack 40. When the sections of the lifting column are brought into longitudinal alinement the rack portions of each section form a continuous rack. 41 is a cross pin extending through the housing 31^x above the operating lever 35. 42 is a pawl which is mounted upon the cross pin 41 and engages the rack 40 at a point 10 above the pawl 38. The pawl 42 is provided with a central slot 43 for a purpose 15 which will hereinafter appear. 44 are spring fingers which are rigidly connected to or formed integral with the pawl 42. The fingers 44 extend downward in a curved direction at each side of the operating lever 20 35 and then upward into contact with the outer face of the upper portion of the block 5. 45 is a cross bar carried by the fingers 44 below the operating lever 35. 46 is a cross pin extending through the housing 25 31^x above the cross pin 41 and slightly to the outside thereof. 47 is a rocking member carried by the cross pin 46 and provided with an upwardly extending arm 48 to which are secured curved springs 49 and 30 50. The spring 50 curves inward toward the lifting column 10 and at a point adjacent thereto curves downward to the lifting pawl 38. The lower end of the spring 50 is provided with an outturned portion or 35 51 to form a stop. 52 is a right angular lug extending upward from the pawl 38 and provided with an orifice through which the downward curved portion of the spring 50 passes for a purpose 40 which will hereinafter appear. The upper end of the spring 49 is secured to a cross pin 53 secured to the side walls of the housing 31^x. The rocking member 47 is provided with a depending tongue 54 which in- 45 clinches normally slightly inward. 55 is a tubular handle for the operating lever 35. The inner end of the handle 55 is provided with projecting portions 56 and 57 extending therefrom at diametrically opposite 50 points. The handle 55 is provided with a slot 58 into which extends a pin 59 carried by the operating lever 35. The upper pawl 42 is provided with an upward extension or finger 60. 61 is a short shaft extending 55 through the wall of the housing 31^x and provided at its inner end with a finger 62 adapted to engage the finger 60 and at its outer end with an operating handle 63.

Having described the principal parts involved in my invention, I will briefly describe the operation of the same.

The parts as shown in Fig. 1 are arranged for raising the lifting column so as to lift the vehicle or other object desired. After 65 placing the jack in position with the lifting

column beneath the part of the vehicle or other object with which it is to engage, I swing the operating lever in a vertical plane thereby carrying the pawl 38 downward during the upward movement of the handle 70 55 to engage a new tooth. When the pawl 38 has engaged the new tooth the handle 55 is swung in the opposite direction so as to force the lifting column upward. During this operation the pawl 42 merely rides over the teeth of the rack 40 passing into engagement with each tooth by means of the spring 44, so as to lock the column after each upward movement and to allow for the return movement of the operating lever. It will be 75 noted that during this operation the movement of the operating lever is not sufficient to carry it into engagement either with the cross bar 45 or with the tongue 54. When it is desired to lower the jack I turn the handle 80 55 a quarter turn so that the projections 56 and 57 are carried from a horizontal position to a vertical position between the cross bar 45 and the tongue 54. I then depress the handle 55 to carry the lower projection 57 85 into engagement with the cross bar 45. By continuing the downward pressure the spring finger 44 is compressed against the block 5 exerting a tension upon the pawl 42 forcing it into the position indicated in Fig. 90 2. The operating handle 55 is then raised, carrying the pawl 38 downward and allowing the lifting column 10 to operate sufficiently to allow the upper pawl 42 to engage with the next succeeding tooth. When the 100 operating lever nearly reaches the limit of its upward stroke or in other words when the lifting column has dropped almost to the limit of its movement the projection 56 engages the tongue 54 forcing such tongue inward and exerting a pull upon the curved spring 50. It will be noted that during the downward movement of the pawl 38 the spring 50 passes through the orifice of the lug 52 carrying the enlarged or turned end 105 51 of the spring 50 into engagement with such lug. It will therefore be seen that as soon as the lug 56 engages the tongue 54 the tension exerted thereby on the spring 50 is sufficient to pull the pawl 38 out of engagement with the rack. When this action takes place the lifting column drops until the upper pawl 42 has fully entered the succeeding tooth with which it had been carried into engagement by the preceding operation. In 110 order that the sections of the lifting column may be automatically locked together to form a solid column as they come to a vertically alined position, I have provided the locking pin 29 and the parts co-acting therewith with the use of which I will now describe. As each section travels upward through the vertical channel formed by the cross wall 7 and opposing portion of the block 5, the pin projections 28 pass upward through the 115 120 125 130

vertical portions of the grooves 8 toward the offset portions 9. When the pin projections have reached this position two adjacent sections which have entered the aforesaid channel are brought into vertical alinement or into a position where the cross lugs 22 fit completely into the recesses 21. When the lugs 22 are in this position the orifice 24 is in horizontal alinement with the orifice 25. 5 When the orifices are in this position the pin projections enter the offset portions and are forced in an outward direction. This operation forces the locking pin 29 also outward so as to enter the orifice 24 locking the 10 parts together. Simultaneously with this operation the projection 33 passes from the recess 31 into the recess 32 so as to definitely hold the locking pin in the locking position. When the jack is operated to lower the lifting 15 column the reverse of this operation of course takes place, that is to say the pin projections 28 are forced in the opposite direction to withdraw the locking pin from the orifice 24 and at the same time carry the 20 projection 33 to the recess 31 thereby holding the locking pin definitely in the withdrawn position. As the locking pin is withdrawn the sections will swing freely upon their hinge pins 20 so as to follow the curve 25 of the casing 1 and thereby assume a compact position. It will of course be understood that if desired the casing 1 might be extended horizontally instead of curving upward so as to accommodate a greater 30 length of column and thereby increase the lifting capacity of the column. If it is desired to drop the load all it is necessary to do is to press upon the handle 63 so as to force the fingers 62 into contact with the finger 60, 35 to draw the pawl 42 out of engagement with the rack. The pawl 38 of course may be withdrawn simply by raising the operating lever to the upper position.

From this description it will be seen that 40 I have devised a very simple form of jack which will be extremely compact and will allow of raising the object to be lifted to a far greater height than would otherwise be the case.

50 What I claim as my invention is.

1. A lifting jack comprising a casing adapted to rest upon the ground and having an upwardly presented orifice and a vertical channel leading therefrom into the casing, a 55 lifting column comprising a series of sections hingedly connected together so as to fit in longitudinal alinement within the vertical channel and to fold on their hinged joints within the casing, a ratchet rack 60 forming the outer face of each section, an operating lever pivotally mounted within the casing, a lower pawl pivotally carried by the lever and engaging the rack of the column, spring means for holding the upper pawl in 65 engagement with the rack, and means for

automatically locking the segments together as they are drawn into longitudinal alinement within the aforesaid channel.

2. A lifting jack comprising a casing adapted to rest upon the ground and having an upwardly presented orifice and a vertical channel extending from such orifice into the casing, a lifting column comprising a series of sections hingedly connected together in proximity to the inner faces thereof, each section having a cross slot concentric with the center of each hinged connection, a correspondingly formed lug extending from the adjacent end of the next successive section adapted to fit within said cross slot, a ratchet rack forming the outer face of each section, means for automatically locking the segments together as they are drawn into longitudinal alinement, an operating lever mounted within the casing, a pawl carried by the lever and engaging the ratchet rack, and a spring held pawl mounted within the casing also engaging the ratchet rack. 70 75 80

3. A lifting jack comprising a casing adapted to rest upon the ground and having an upwardly presented orifice and a vertical channel extending from such orifice into the casing and having opposing grooves in the walls thereof extending vertically at each side of the aforesaid channel and having an offset therein and curving longitudinally at each side of the casing, a lifting column comprising a series of sections each section having a recess in its inner face and opposing cross slots in the side walls thereof 90 95 100 and an orifice extending through the inner wall of the recess, a hinged connection between each of the sections, a lug carried by the end of each section next adjacent to the aforesaid recess and having an orifice therein adapted to be brought into a line with the aforesaid orifice when the sections are carried into longitudinal alinement, a cross piece fitting into each recess of each section and having pin projections extending into the cross slots of the sections and into the opposing grooves of the casing, a locking pin extending from the cross piece into the orifice of the recess wall adapted to be forced into the orifice of the lug when the sections are brought into longitudinal alinement and the pin projections into the offset portions of the opposing grooves of the casing, an operating lever pivotally mounted within the casing, and means operated thereby for drawing the sections successively from the casing into the vertical channel. 110

4. A lifting jack comprising a casing adapted to rest upon the ground and having an upwardly presented orifice and a channel extending inwardly from such orifice and a groove formed in each side wall of the casing and extending vertically at each side of the channel and having an offset portion therein and the inner end curving hori- 115 120 125 130

- zontally in each side wall of the casing, a lifting column comprising a series of sections hingedly connected together each section being provided at one end with a cross slot concentric to its hinged center, a correspondingly formed lug extending from the next adjacent section and fitting within the cross slot, a cross piece carried by each section to move crosswise thereof, a pin projection extending from each end of the cross piece into the grooves of the casing, and means carried by the cross piece adapted to engage with the cross lug of the next adjacent section as the pin projections enter the offset portions of the grooves and means for imparting a step by step movement to the lifting column to carry the sections successively from the casing into longitudinal alinement within the channel.
5. A lifting jack comprising a casing having an upwardly presented orifice and a vertical channel extending inwardly from such orifice, a lifting column comprising a series of sections hingedly connected together and adapted to fit within the casing and successively enter the channel, a ratchet forming the outer face of each section, an operating lever pivoted within the casing, a pawl carried by the operating lever engaging the ratchet rack of the lifting column, a pawl carried by the casing and spring held in engagement with the ratchet rack of the lifting column and adjustable means carried by the operating lever and co-acting means carried by the casing for drawing the pawls alternately out of engagement with the rack to permit of a lowering movement.
6. A lifting jack comprising a casing having an upwardly presented orifice and a vertical channel leading inwardly therefrom, a lifting column comprising a series of sections hingedly connected together, a ratchet rack forming the outer face of each section, an operating lever mounted upon the casing, a pawl carried by the lever and engaging the ratchet rack, a holding pawl mounted upon the casing and also engaging the ratchet rack, curved spring fingers depending from the lower end of the holding pawl and having their curved ends bearing against a suitable portion of the casing, a rocking member mounted upon the casing, a tension spring carried by the rocking member and slidably extending through a suitable portion of the pawl of the operating lever and having a stop portion at its end, a projection carried by the spring fingers of the holding pawl and a projection carried by the rocking member, a pin extending from the operating lever, a tubular handle for the lever having an arc shaped slot into which the pin extends and diametrically opposite projections extending from the inner end of the handle adapted to be interposed between the projections of the spring fingers, of the holding pawl and the projection of the rocking member to alternately compress the spring fingers of the holding pawl and to draw into tension the spring of the rocking member when the operating lever is alternately lowered and raised.

7. A lifting jack comprising a casing having an upwardly presented orifice and a vertical channel leading inwardly therefrom, a lifting column comprising a series of sections hingedly connected together, a ratchet rack forming the outer face of each section, an operating lever mounted upon the casing, a pawl carried by the lever and engaging the ratchet rack, a holding pawl mounted upon the casing and also engaging the ratchet rack.

8. A lifting jack comprising a casing having an upwardly presented exit orifice, a vertical guide way located within the casing, a normally flexible lifting column extending at its upper end into the guide way and laterally therefrom at its lower end, an operating lever for forcing the column vertically, a turnable handle therefor, and means controlled by the turning of the handle on the lever for changing the direction of the movement of the lifting column.

ANTHONY GUSTIANA.
